Primary Examiner — Cynthia Ramirez*Assistant Examiner* — Michael A Maharajh(74) *Attorney, Agent, or Firm* — Santangelo Law Offices, P.C.(57) **CLAIM**

The ornamental design for a handheld tissue manipulation tool, as shown and described.

DESCRIPTION

FIG. 1 is a left side view of the handheld tissue manipulation tool, showing our new design;

FIG. 2 is a right side view thereof;

FIG. 3 is an upper left perspective view thereof;

FIG. 4 is an upper right perspective view thereof;

FIG. 5 is a front view thereof;

FIG. 6 is a rear view thereof;

FIG. 7 is a top view thereof; and,

FIG. 8 is a bottom view thereof.

The broken lines in the drawings are for the purpose of illustrating portions of the handheld tissue manipulation tool that form no part of the claimed design.

1 Claim, 8 Drawing Sheets(56)
